UNITED STATES PATENT OFFICE

CARL GABRIELSON, OF SYRACUSE, NEW YORK, ASSIGNOR TO L C SMITH & CORONA
TYPEWRITERS INC., OF SYRACUSE, NEW YORK, A CORPORATION OF NEW YORK

KEY-SET TABULATOR FOR TYPEWRITING MACHINES

Application filed March 4, 1926. Serial No. 92,307.

This invention relates to improvements in tabulating mechanism for typewriting machines of the general character illustrated in U. S. Letters Patent 971,696 dated Oct. 4, 1910. 55
5 In this patent the tabulator stop bar or rack is provided with notches or guides corresponding to each letter space movement of the carriage and in each notch or guide a movable stop is permanently mounted. A key operated finger is so located adjacent to the rack that it will move one of the stops into operative position when the key is operated, the stop selected corresponding to the position of the carriage. The stops are yieldingly held either in operative or inoperative position and means are provided for simultaneously restoring the stops from the operative to the inoperative position. 60

on its front and rear sides slots 13, 14 to receive the stops, there being a pair of these slots 13, 14 for each letter space movement of the carriage. The rack may be secured at its ends to the carriage in any suitable way. As shown in Figures 4, 6 and 7 the teeth between the slots 13 have upper and lower V-shaped notches 15, 16 which are adapted to cooperate with spring detents 17 on the stops 18. Each stop has a central opening the walls 19 of which slide in the grooves 13, 14 and a rear projection 20 which cooperates with any one of a series of stop levers 21 which levers are pivoted at 22 in the machine frame and are operated by the usual tabulator keys, not shown. The rear leg 19 of each stop has a downward extension 19^a which assists in guiding the stop on the rack.

The present invention relates to various improvements in details designed to adapt a key set tabulator of the type described to a modern typewriting machine, to simplify its construction and to render its operation more positive. 75

The invention will be more particularly described with reference to the accompanying drawing, in which—

Fig. 2 is a section about on the line 2—2 of Figure 1;

Fig. 3 is a plan view of the tabulating mechanism;

Fig. 4 is a perspective view of a part of the stop bar or rack and one of the stops;

Fig. 5 is a section on the line 5—5 of Figure 1;

Fig. 6 is a section on the line 2—2 of Figure 1 illustrating the operation of setting a stop; and

Fig. 7 is a similar view illustrating the manner of clearing all of the stops, that is, of moving them from operative to inoperative position.

Referring to the drawing, 10 indicates the frame of the machine and 11 a part of the carriage which travels on suitable ball bearing. Apart from the tabulating mechanism the machine shown is the well known L C Smith typewriter. The carriage is provided with the tabulator stop rack 12 which has

23 normally rests against the blade, as shown in Figures 2 and 7.

5 The device for simultaneously raising any stops from operative to inoperative position comprises blade or universal bar 30 which extends lengthwise of the rack and lies below the rear legs 18 of the stops, as shown in Figures 6 and 7. The blade 30 is also pivotally mounted in the end plates 28 of the 10 tabulator frame and it is held in its lower or inoperative position normally by means of a spring 31 coiled around its pivot, as shown in Figure 3.

15 The restoring blade 30 is rocked by means of a crank 32 pivoted in one of the ends 28 of the tabulator frame, as shown in Figure 5. Connected to the crank is a disk 33 carrying an anti-friction roller 34 which lies under an arm 35 connected with the restoring blade 30. The disk 33 is preferably provided with stop shoulders 36, 37 cooperating with a fixed pin 38 to limit the movement of the lever 32. One of these shoulders 37 limits the movement of the lever and of the 25 blade 30 so that the blade will raise the stops exactly to their normal position when the lever is moved, that is, to the position which the spring pawl on the stop will engage the upper notch in the rack. In Figure 6 the 30 blade 30 is shown in its lowermost position, which permits any one of the stops to be fully depressed, and in Figure 7 the blade 30 is shown at the upper limit of its movement. It will be noted that the blade 30 35 underlies the stops adjacent to the holding pawls and hence the thrust of the blade is most directly applied to withdrawing the pawls from the lower notches in the rack bar and does not tend to tip the stops on the 40 bar.

45 The stops are locked in position on the rack bar by a rod 39 which engages the projecting shoulders 40 on the rear sides of the stops when they are in their upper position, as shown in Figure 7. It will be understood that in the operation of the machine as many stops are used on the tabulator rack as there are notches or grooves in the rack, that is, a stop is provided for each letter space movement of the carriage. The locking rod 39 50 is detachably secured in the end plates 28 of the tabulator rack so that defective stops may be removed and replaced when desired.

55 The operation of the device will be understood from the foregoing description. Whenever it is desired to set a tabulator stop for a particular piece of work, the carriage is brought into the position at which the stop is to take effect, as determined by the scale 60 and the finger key 27 is then depressed to throw the selected stop down into operative position. This is repeated for each stop desired. The machine is then operated in the usual manner and when the selected stops are 65 no longer necessary, the lever 32 is operated

to rock the restoring blade 30 and raises all of the stops to normal inoperative position on the bar.

An important feature of the present invention consists in mounting both the devices for 70 setting the tabulator stops and the devices for restoring said stops to inoperative position on the carriage whereby the tabulating mechanism may be completely controlled without resort to the keyboard and without 75 removing the hands from the carriage. This has been found to be a great convenience and to save considerable time in tabulating work. Thus the operator, with one or both hands on the carriage, moves the carriage to the 80 position at which a tabulator stop is required, and then sets the stop by depressing the key 27. In fact, the operator may select a stop and set it by simply grasping the key 27, moving the carriage to the proper point, and then depressing the key. Heretofore, it has been customary to set the carriage and then lower the hand to the keyboard to adjust the selected stop.

Having thus described the invention what 90 is claimed as new and desired to be secured by Letters Patent is:

1. In a tabulating mechanism for type-writing machines the combination with a tabulator rack mounted on the carriage, and tabulating stops movable on said rack, of an arm pivoted on the frame of the machine and overlying said rack and stops and a blade or universal bar pivoted on the carriage and adapted when rocked to depress the arm and set a stop to operative position. 95

2. In a tabulating mechanism for type-writing machines the combination with a tabulator rack mounted on the carriage, and tabulating stops movable on said rack, of an arm pivoted on the frame of the machine and overlying said rack and stops and a blade or universal bar pivoted on the carriage and adapted when rocked to depress the arm and set a stop to operative position, said 100 arm being normally raised by spring means into contact with the universal bar and said bar being provided with a finger lever for depressing the same. 110

3. In a tabulating mechanism for type-writing machines, a tabulator rack having grooves on opposite sides thereof, a series of tabulator stops mounted in said grooves and movable therein between operative and inoperative positions, each stop having a 115 spring detent for holding it yieldingly in either position and a blade or universal bar pivotally mounted exterior to the rack and adapted when rocked to move all of the stops to inoperative position. 120

4. In a tabulating mechanism for type-writing machines, a tabulator rack having grooves on opposite sides thereof, a series of tabulator stops mounted in said grooves and movable therein between operative and 130

inoperative positions, and a blade or universal bar pivotally mounted exterior to the rack and adapted when rocked to move all of the stops to inoperative position, an arm on said bar, a spring for holding said universal bar in inoperative position and a lever having a roller acting on said arm for operating said bar against the tension of the spring.

5 10 5. In a typewriting machine, the combination with a frame and a pivoted arm mounted on the frame, of a carriage movable on the frame, a tabulator rack fixedly mounted on the carriage, a series of stops adjustably mounted on the rack, and devices movably mounted on the carriage and cooperating with the arm for moving selected stops from inoperative to operative position, said devices comprising a universal bar and a key 15 20 for operating said bar, both mounted upon the carriage.

6. In a typewriting machine, the combination with a frame and pivoted arm mounted on the frame, of a carriage movable on the frame, a tabulator rack fixedly mounted on the carriage, a series of stops adjustably mounted on the rack, a device movably mounted on the carriage and cooperating with the arm for moving selected stops from inoperative to operative position, and a second device mounted on the carriage for restoring the stops to inoperative position.

7. In a typewriting machine, the combination with a frame and a pivoted arm mounted on the frame, of a carriage movable on the frame, a tabulator rack fixedly mounted on the carriage, a series of stops adjustably mounted on the rack, a device movably mounted on the carriage and cooperating with the arm for moving selected stops from inoperative to operative position, and a second device mounted on the carriage for restoring the stops to inoperative position, each of said devices comprising a universal bar 40 45 mounted on the carriage, and hand-operated means on the carriage for moving said bars.

In testimony whereof I hereunto affix my signature.

CARL GABRIELSON.
